DESIGN FOR A SCREW CAP REMOVING IMPLEMENT

Harry Francke, Kansas City, Mo.

Application January 30, 1939, Serial No. 82,661

Term of patent 7 years

To all whom it may concern:

Be it known that I, Harry Francke, a citizen of the United States, residing at Kansas City, in the county of Jackson and State of Missouri, have invented a new, original, and ornamental Design for a Screw Cap Removing Implement, of which the following is a specification, reference being had to the accompanying drawing, forming a part thereof.

Figure 1 is a side elevation of the screw cap removing implement showing my new design.

Fig. 2 is an edge elevation thereof; and,

Fig. 3 is an end elevation of the screw cap removing implement.

I claim:

The ornamental design for a screw cap removing implement, as shown.

HARRY FRANCKE.
